UNITED STATES PATENT OFFICE

CHARLES SEIDMAN, OF PHILADELPHIA, PENNSYLVANIA

DESIGN FOR A SWEATER

Application filed May 29, 1930. Serial No. 35,845. Term of patent 3½ years.

To all whom it may concern:

Be it known that I, CHARLES SEIDMAN, a citizen of the United States, residing in the city and county of Philadelphia, State of Pennsylvania, have invented a new, original, and ornamental Design for Sweaters, of which the following is a specification, reference being had to the accompanying drawing, forming part thereof.

The figure is a diagrammatic face view of a sweater, showing my new design, as applied to the front of said sweater, the back thereof being plain.

I claim:—

The ornamental design for a sweater, as shown and described.

CHARLES SEIDMAN.
